FIGURE TOY.

Application filed November 30, 1921. Serial No. 518,754.

To all whom it may concern:

Be it known that we, DANIEL F. WHITCOMB and KARL R. COOLIDGE, both citizens of the United States, and residents of the 5 city of Los Angeles, county of Los Angeles, State of California, have invented new and useful Improvements in Figure Toys, of which the following is a specification.

Our invention relates to toys, primarily 10 designed for the amusement of children in which certain of the parts thereof are caused to imitate certain movements of men, and the object thereof is to produce simple and inexpensive toys for that purpose.

15 In the drawings forming a part of this application we have illustrated a toy in which the figures represent boxers who by certain movements are caused to strike each other as in boxing contests. Fig. 1 is a side elevation of our toy with the platform partly in 20 section. Fig. 2 is a side elevation partly in section of one of the boxers and a part of the platform shown in Fig. 1.

25 Referring to the drawings the boxers 6 and 7 are mounted on a platform. As both boxers are constructed and operated in the same way only one boxer will be described in detail. Referring to boxer 6 the head is marked 8 and the body 9. A pedestal 10 extends from the body to the top 11 of the platform and is then reduced in size and passes through the top of the platform and to a distance below. Below the top and secured upon the projecting end of pedestal 10 30 is a large thick washer 12. Secured to the lower portion of the body are jointed legs 13 which terminate in feet 14. Secured to the upper portion of the body are jointed arms 15 which arms terminate in knobs 16 representing boxing gloves. Passing through 35 channels in the left leg members, through the body and through the right arm members is a cord 17, one end of which is secured to the platform and the other end is secured to the knob at the end of that arm. Passing 40 through channels in the right leg members, through the body and through the left arm members is a cord 18, one end of which is secured to the platform and the other end

is secured to the knob at the end of that arm. 50 The sides 19 and ends 20 of the platform support the top when the toy is on a table out of use.

Operation.

55 The child takes the toy and grasps the washers on the ends of the pedestal of both figures between the thumbs and fingers of his hands and gives them a quick rotative movement, first in one direction and then in 60 the other. As one end of each cord is fixed to the platform the rotation of the figure causes the arms of the figure to fly up and around and to strike the other figure which is so placed that the gloves of one figure 65 will strike the head and body of the other figure when a rotative movement is given the body. One of the boxers could be used with a platform.

Having described our invention we claim. 70
 1. A figure toy comprising a platform, a body having a head and four jointed members, two being upper members and two being lower members, said body terminating in a pedestal rotatively mounted in the platform; cords connected to the platform and each cord passing through the lower jointed members thence through the body, thence through the upper jointed members on the opposite side of the body and secured to the 75 outer ends of said upper members.

2. A figure toy comprising a platform, two bodies having heads, each body having two upper jointed members and two lower jointed members; pedestals secured to said bodies 80 said pedestals being rotatively mounted in said platform; cords connected to the platform and passing through the members and bodies and secured to the outer ends of the upper members, each cord passing through 85 a lower member on one side, and an upper member on the other side, of the body and through the body.

In witness that we claim the foregoing we have hereunto subscribed our names this 90 16th day of November, 1921.

DANIEL F. WHITCOMB.
KARL R. COOLIDGE.
